UNITED STATES PATENT OFFICE.

CARL SCRABIC, OF URBANA, OHIO

SOUND-BOX STRUCTURE.

Application filed April 28, 1920. Serial No. 377,221.

To all whom it may concern:

Be it known that CARL SCRABIC, a citizen of the United States, residing at Urbana, in the county of Champaign and State of 5 Ohio, has invented certain new and useful Improvements in Sound-Box Structures, of which the following is a specification.

This invention relates broadly to talking machines, and has particular reference to 10 the sound reproducing mechanism thereof, the object of the invention being fundamentally to provide a sound box of such construction that the same will automatically act to position itself in such manner that 15 its needle or stylus will be properly centered in the groove of a record with which the sound box is employed, the construction being such that the stylus will be located in the center of gravity of the sound box and 20 will be maintained in proper relationship with the record irrespective of position variations which the latter may assume during its rotation.

Another object of the invention resides 25 in the provision of an improved connection or mounting between the tubular outlet end of a sound box and the forward end of a tone arm, said mounting consisting of a plurality of concentric rings which are provided with independent angularly located 30 pivots, the arrangement of the rings and pivots being such that the sound box may be freely suspended so that its stylus will by virtue of the weight of the sound box, be 35 maintained in proper engagement with record grooves, the pivot construction allowing for lateral movement on the part of the sound box and also for similar vertical movement, said mounting, allowing the stylus of 40 the sound box to be properly positioned within the record grooves even when the record is not rotating on a true horizontal plane.

A further object of the invention resides 45 in constructing the sound box so that the same may be adapted for reproducing purposes in connection with both lateral and vertical cut records and to provide adjustable weight means in conjunction with 50 the sound box, whereby its effective weight may be varied to properly adapt the same to the particular type of record with which the sound box is being used.

With these and other objects in view, as 55 will appear as the description proceeds, the invention accordingly consists in the novel

features of construction, combinations of elements and arrangement of parts, hereinafter to fully described and to have the scope thereof pointed out in the appended 60 claims.

In the accompanying drawing, forming a part of this specification and in which similar characters of reference denote like and corresponding parts:

Figure 1 is a vertical sectional view taken through the improved sound box construction and its cooperative mounting.

Figure 2 is a front elevation thereof.

Figure 3 is a horizontal sectional view 70 taken through the mounting on the line 3-3 of Figure 1.

Figure 4 is a detailed view disclosing more particularly the construction of the upper part of the sound box stylus, and,

Figure 5 is a horizontal sectional view 75 disclosing the weight adjusting mechanism.

In the accompanying drawings there has been shown for purposes of illustration the deck 1 of a talking machine. This deck is 80 provided with the usual rotatable turn table or record support 2 which is operated by means of a motor driven spindle 3. A record of any suitable type 4 may be imposed in the usual manner upon the upper surface 85 of the turn table for cooperating with the sound box 5 of the talking machine. As usual, the sound box is carried by the outer end of a swinging tone arm 7, the latter being mounted for pivotal movement within a 90 bearing 8 provided upon the deck 1. It will be understood that the stylus 9 of the sound box is adapted to engage in the usual manner with the grooves of the record 4, but owing to the spiral formation of such 95 grooves, the tone arm and sound box will be oscillated across the playing face of the record.

The sound box 5 consists of a wooden inverted bowl or shell 10 which is formed 100 to terminate in a reduced and shouldered neck portion 11 which is in direct communication with a wooden supporting tube 12, the upper end of the latter being connected in a manner to be hereinafter described with the outer end of the tone arm 7. To connect the neck portion 11 with the tube 12, the latter is provided with a fixed metallic cup 13 upon its lower end, which cup is formed with an out-turned flange disposed 105 for swiveled engagement with an in-turned flange 14 formed on a metallic ring 15,

which is carried in a threaded manner by the shell 10, and a packing 16 may be interposed between the adjoining surfaces of the shell 10 and the tube 12 in order to insulate the sound conduit therein from the metallic parts 14 and 15. Obviously, through this construction, the position of the sound box may be altered by rotation, in order that said sound box may be adapted to the different types of records.

In this instance, the lower annular edge of the shell 10 is provided with metal annulus 17, which is suitably secured in position in connection with the shell in any desired manner. The interior of the annulus is provided with a recess 18 which is closed by means of an adjustable ring 19 carried by the annulus. Positioned within the recess 18 is a plurality of gaskets 20 between certain of which there is clamped the diaphragm 21 of the sound box. This diaphragm is preferably formed from metal or an equivalent substance and is of dish formation instead of being of the usual flat construction. The center of the diaphragm is arranged for cooperation with the free end 22 of an oscillating stylus 23, and it will be seen upon reference to Figure 1, that the diaphragm is preferably formed with a plurality of undulations. These undulations are quite marked at the center of the diaphragm and gradually decrease in depth toward the outer circumferential edge of the diaphragm. This construction results in increasing the vibratory area of the diaphragm and also adapts the latter to the natural sound wave curvatures. This construction may be likened to the dropping of a pebble in a body of water, from which it will be observed that the ripples produced are most pronounced in the water in which the pebble is dropped, and that the ripples gradually decrease in depth in circumferential waves or undulations from that particular point. In other words, the construction of the diaphragm 21 is such that the same will adapt itself over its entire area to clearly reproduce the vibrations delivered thereto by reason of its engagement with the stylus 9.

The stylus itself is carried by means of a conical casing 24, which latter has its outer circumferential edge secured in place between certain of the gaskets 20. The apex of the casing 24 is provided with a bearing member 25, the latter carrying pivot screws 26 by means of which the stylus is pivotally mounted for substantially free swinging movement. The lower end of the stylus may be equipped with the usual thumb screw 27 by means of which a needle or the like 28 may be detachably connected therewith. The upper end of the stylus 23 is curved and reduced in thickness, as is indicated by the numeral 29. This con-

struction results in rendering the stylus extremely sensitive and susceptible to the faintest movements created by the needle 28 with the undulations of the record 4.

The sound box is connected with the free end of the tone arm 7 by means of the mounting 30. This mounting preferably consists of a ball bearing raceway 31 which is provided in the end of the tone arm. Freely mounted for rotation within the raceway 31 is a metallic annulus 32. This annulus carries concentrically within the same a ring 33, which, in turn, receives the concentric upper end of the tube 12. The latter is provided with an offset flange upon its upper end which retains in position a wear collar 34. As is clearly shown in Figure 3, the annulus 32 is provided with a pair of diametrically aligned pivot screws 35 whose point ends are arranged to engage with bearing depressions formed in the outer edge of the ring 33. When the parts are positioned in the manner shown in Figure 1, it will be manifest that the provision of the screws 35 will permit of upward or vertical oscillation on the part of the sound box, the outer edge of the ring 33 being suitably curved so that the same will be permitted to oscillate within the confines of the annulus 32 and without binding upon the latter. Similarly, the ring 33 is provided with pivot screws 36 which are disposed to engage with bearing depressions formed in the collar 34. These screws 36 are located at right angles to the screws 35 and hence are capable of permitting of oscillatory lateral motion on the part of the sound box structure. The outer face of the collar 34 is curved on a suitable radius to prevent said collar when being oscillated from binding itself in engagement with the inner edge of the ring 33. The upper end of the tube 12, of course, opens freely into the tone arm 7, so that a sound conduit may be provided through the sound box structure into the interior of the tone arm.

By virtue of the construction described, it will be manifest that a sound box is provided which will automatically maintain in proper relationship with a cooperative record. It is a well known fact that records have a tendency to warp and that frequently the turn tables themselves are not so located as to rotate on a true horizontal plane. These conditions, among others, tend to permit a record to wobble, as it were, when being reproduced and this undulating rocking motion normally tends to cause improper contact between the needle 28 and the record so that scratching and grating sounds are set up thereby. In the present invention, the sound box is freely suspended from an elevated point and is adapted for substantially universal movement. That is,

the sound box may rotate horizontally by reason of the engagement of the annulus 32 with the ball bearing raceway 31, and this movement may take place with but a minimum of friction by reason of the anti-friction bearings provided. Further, vertical movement of the sound box is taken care of by the pivot screws 35 carried by the annulus 32 and lateral movement is provided for by reason of the screws 36. All of these movements serve to allow the stylus construction of a sound box to automatically adapt itself to variations in the operative position of a record, and directly tend to eliminate undue friction between the stylus and the walls defining the grooves of a record. This results in a reduction in friction between the stylus and record and hence an absence of grating or scratching noises in the finally reproduced music. Furthermore, the sound box and tone arm construction provides a sound conduit having resonant walls preferably formed from wood, a feature which also tends to minimize discordant notes. It will be observed that the needle 28 is positioned exactly in the center of gravity of the sound box and not to one side thereof, this feature insures proper engagement between the needle and the record grooves and also tends to minimize undue friction.

Preferably, the tube 12 is provided with a pivoted hollow ring 37, in which a suitable body of mercury is confined. The ring 37 is pivoted centrally as at 38 to the tube 12 and by means of a spring 39 said ring is maintained in the position shown in Figure 1. While in this position, the mercury will flow toward the lower part of the ring, thus causing its weight to be exercised on the side of the center of gravity of the sound box that will cause the latter to oscillate more firmly toward the record. However, when the sound box is given a quarter of a turn to provide for vertical cut records, said ring 37 will be moved to the dotted line position by means of the cam 40, the latter being carried by the upper portion of the sound box shell 10. This results in causing the mercury to flow to the opposite side of the center of gravity of the sound box, thus tending to lighten the weight of the latter and rendering the same particularly adaptable for the reproduction of vertical cut records. The presence of the ring

37 is the result of investigations which have disclosed that when lateral cut records are employed, a sound box structure of greater weight should be utilized than when vertical cut records are to be reproduced. By the presence of the ring 37, this change in weight is automatically accomplished and a sound box structure is provided which may be used with efficacious results in connection with either type of record.

What is claimed is:

1. In a talking machine, a tone arm, a sound box connected with the free end of said tone arm, the connection between said tone arm and sound box being formed to constitute an annulus mounted for rotation in a bearing connected with said tone arm, a ring member located within said annulus and pivotally mounted with respect thereto and an extension formed upon the upper end of said sound box and having pivotal connection with said ring member; the pivotal connection between said ring member and sound box being located substantially at right angles to the pivotal connection between the annulus and ring member.

2. In reproducing mechanism for talking machines, a tone arm, a sound box rotatably connected with the free end of said tone arm and capable of being employed in connection with both vertical and lateral cut records, a mounting formed with said tone arm for effecting a swinging suspension of said sound box, and automatically operated means located between the tone arm and sound box capable of varying the effective pressure upon the stylus of said sound box in accordance with the operative position of the latter.

3. In sound reproducing mechanism for talking machines, a combination with a swinging tone arm, of a sound box movably suspended from the free end of said tone arm, means permitting of the rotation of said sound box relative to said tone arm to adapt the same to both vertical and lateral cut records and an adjustable fluid container cooperative with said sound box and capable of varying the effective pressure upon the stylus of the latter in accordance with the operative position occupied by the sound box.

In testimony whereof I affix my signature.

CARL SCRABIC.
